RADIO RECEIVING SET

Stuart W. Seeley and Garrard Mountjoy, Jackson,
Mich., assignors, by mesne assignments, to
Radio Corporation of America, New York, N. Y.,
a corporation of Delaware

Application October 20, 1932, Serial No. 638,752

6 Claims. (Cl. 250—20)

This invention relates to radio receiving sets and is particularly useful in receiving sets of the superheterodyne type where an oscillator beats with the desired signal to produce a super-audible intermediate frequency.

In superheterodyne sets the oscillator combines with two frequencies to produce the same intermediate frequency. One of these is above the oscillator frequency and the other one below it. For example, a superheterodyne oscillator having a frequency of 1175 k. c. will produce an intermediate frequency of 175 k. c. with a signal of 1000 k. c. or with another signal of 1350 k. c.

In superheterodyne receiving sets a number of circuits tuned to the desired signal frequency precede the frequency changer or first detector and thus amplify the desired signal without appreciably amplifying the other undesired frequency which is usually called the image of the desired signal. However, unless an undue amount of radio frequency tuning is employed there still remains an objectionable amount of image frequency to interfere with the signal.

It is the object of our invention to use a minimum amount of radio frequency tuning ahead of the oscillator to lower the cost and to eliminate the image frequency by balance circuits which are of relatively low cost compared to the usual tuning stages.

The manner in which the balance circuits are employed will now be described, reference being had to the drawing, in which:

Fig. 1 is an illustration of the circuits in which the invention is used, the parts not directly involved in the invention being shown conventionally.

Fig. 2 is an illustration of the balance circuits in a simpler form and disconnected from the rest of the receiving set.

Referring to Fig. 1, the antenna 1 is connected to coupling condenser 2 and ground 3 through a tuned couple consisting of inductance 4 and capacity 5, the latter being variable to permit tuning for various signals. One stage of tuning is all that is employed in the illustrated circuit and the resonant voltage of the tuned couple is applied directly to the grid 6 of a vacuum tube 6'. This vacuum tube is shown as a three-element tube for simplification but of course a screen grid tube or a pentode (five element tube) or other suitable tube may be used. The filament

7 in practice usually is fed from a power supply, but for simplicity, it is illustrated as connected to a simple A source 8, the filament be-

ing connected to ground 3 through a small condenser 9 and resistance 10.

The plate of the tube 11 is connected to the first detector illustrated conventionally and to the positive terminal of the B supply preferably through a radio frequency choke 12. The negative terminal of the B supply is connected to ground but to reduce the resistance we preferably employ a resistor 13 in shunt to the series circuit containing condenser 9 and resistance 10. In practice, it is usual to have one power supply to furnish the filament and plate voltages, but for simplicity, the complete power apparatus has not been shown.

In general, the desired signal received on the antenna 1 is increased in voltage by the tuned circuit 4, 5, and amplified by the vacuum tube 6'. This amplified signal is then introduced into the detector circuit 14 where it combines with the output of oscillator 15 and is detected to produce the super-audible intermediate frequency. This intermediate frequency is then amplified at 16 and detected again at 17 to produce an audio frequency. This audio frequency is amplified at 18 and heard in the phones 19 which in practice usually would be some form of loud speaker.

While the signal is being received the image frequency is also impressed on the grid 6 of the radio frequency amplifier if a station of that frequency is operating at the time. While this image frequency does not have its voltage materially increased by the tuned couple 4, 5, it nevertheless is of such value as to produce an objectionable interfering signal in the indicating device 19. The manner in which this image frequency is balanced out will be best understood by referring to the circuits in Fig. 2. This figure illustrates the six arm Wheatstone bridge circuit. In this bridge the arm E consists of the antenna-ground circuit and the conjugate arm F consists of the vacuum tube amplifier and its associated first detector and heterodyne oscillator, the latter being omitted in Fig. 2 for simplicity. The arm A consists of the capacity 2 while its conjugate arm D consists of the capacity 9 and the resistances 10 and 13. The arm B consists of the inductance 4 and capacity 5 made resonant to the desired signal and its conjugate arm C consists of a condenser 20 and inductance 21 having a resonant point above the image of the signal to which the loop 4, 5 is capable of being tuned.

Since the grid 6 is connected to the point 22 of this bridge and the filament is connected to the point 23 thereof the desired signal is im-

pressed directly between the grid 6 and the filament 7 because the tuned circuit 4, 5, unbalances the circuit for the desired signal. By properly proportioning the condenser 20, coil 21, condenser 9 and resistances 10 and 13, the bridge may be substantially balanced for the image frequency throughout the broadcast band so that the points 22 and 23 are at substantially the same potential in respect to the image.

10 The invention is not limited to any particular proportioning of parts but, by way of example, we will say that good results have been obtained by making the coupling condenser 2 of 36 micro-microfarads capacity, the coil 4 of 220 micro-henrys, the variable capacity 5 with a maximum capacity of 400 micro-microfarads, the condenser 20 of 43.95 micro-microfarads, the coil 21 of 289 microhenrys, condenser 9 of 500 micro-microfarads, and resistances 10 and 13 of 8 ohms and 20 8,500 ohms respectively.

Assuming that the desired signal for a certain setting of the tuning arrangement is 1000 k. c. and assuming 175 k. c. as the intermediate frequency, the oscillator would have a frequency of 25 1175 k. c. and the image frequency would be 1350 k. c. With these assumptions the apparent or effective capacity of the B arm would be about 35 micro-microfarads for the image frequency because above the resonant frequency the B arm 30 exhibits a capacitative reaction. When the tuning unit is adjusted to 550 k. c. the image producing frequency would be 900 k. c. and the B arm would have an effective capacity of about 250 micro-microfarads for that frequency.

35 To produce substantially no potential drop between the points 22, 23 of the bridge circuit the arms must be proportional so that the product of the impedances of the conjugate arms A and D equals the product of the impedances of arms 40 B and C.

Since the image frequency is always above the signal frequency for the assumed case, the B arm appears as a decreasing effective capacity as the frequency increases. In the C arm, the inductive 45 reactance of inductor 21 subtracts from the capacitative reactance of capacity 21 such that the arm appears as a larger effective capacity as the frequency increases. Hence, as the couple in loop 4, 5, tunes to higher signals in the reception 50 band the balance for the corresponding image frequencies will substantially remain due to the compensating effect in the B and C arms.

The inverse changes in apparent capacity of the arms B and C do not affect the reception of 55 the desired signal as the tuned arm B greatly offsets any small change in capacity in the C arm.

The balancing of image frequency is hindered by a considerable resistance component in the B arm at the higher frequencies and to compensate 60 for this the small resistor 10 is placed in series with the capacity 9. Again this has no effect on the reception of the desired signal. In this balance circuit the capacity 9 is quite small and it is advisable to by-pass the radio frequency currents in the plate circuit directly to the cathode 65 through condenser 24.

In receiving sets that we have designed employing this invention we have reduced the image frequency to a point where it is entirely inaudible 70 over the entire broadcast band, which with only one tuned circuit ahead of the first detector produces a very satisfactory receiver at quite low cost.

Having described our invention, what we claim is:

1. In a superheterodyne receiving set, a bridge circuit consisting of a signal and image frequency source in one arm, means connected to the conjugate of said arm for producing beats with the signal frequency, a substantially constant effective capacity in each of another pair of conjugate arms and means for producing in the third pair of conjugate arms effective capacities that vary substantially inversely with frequency changes within the band defined by the signal and image frequencies. 10

15 2. In a superheterodyne receiving set, a bridge circuit consisting of a signal and image frequency source in one arm, means connected to the conjugate of said arm for producing beats with the signal and image frequencies, means for producing substantially constant effective capacity in each of another pair of conjugate arms, a loop in one arm of the third pair of conjugate arms tuned substantially to the signal frequency and a condenser and inductance in the other arm of the third pair of conjugate arms tuned to a frequency other than the signal frequency. 25

30 3. In a superheterodyne receiving set, a bridge circuit consisting of a signal and image frequency source in one arm, means connected to the conjugate of said arm for producing beats with the signal, means for producing substantially constant effective capacity in each of another pair of conjugate arms, a loop in one arm of the third pair of conjugate arms substantially tuned to the signal frequency and a condenser and inductance in series in the other arm of the third pair of conjugate arms tuned to a frequency beyond the 35 image frequency.

4. In a superheterodyne receiving set, a bridge circuit consisting of a signal and image frequency source in one arm, means connected to the conjugate of said arm for producing beats with the signal, condensers of substantially constant capacity in the arms of a second pair of conjugate arms, an inductance and condenser in parallel in one arm of the third pair of conjugate arms, and 40 a condenser and inductance in series in the other arm of said third pair of conjugate arms. 45

5. In a superheterodyne receiving set, a bridge circuit consisting of a signal and image frequency source in one arm, means connected to the conjugate of said arm for producing beats with the signal, condensers of substantially constant capacity in the arms of a second pair of conjugate arms, an inductance and condenser in parallel in one arm of the third pair of conjugate arms and substantially tuned to the signal, and a condenser and inductance in series in the other arm of said third pair of conjugate arms and tuned above the 55 image frequency.

6. In a superheterodyne receiving set, a bridge circuit consisting of a signal and an image frequency source in one arm, a beating frequency source connected to the conjugate of said arm, impedance elements in another pair of conjugate arms whose ratio of impedances is substantially 60 independent of frequency, impedance elements in a third pair of conjugate arms whose ratio of impedances inherently varies with frequency, and means to adjust one of the last mentioned impedance elements to balance the bridge for the 65 image frequency source and unbalance it for the signal frequency source. 70
